RALPH E. JONES, OF SYRACUSE, NEW YORK, ASSIGNOR TO CROUSE-HINDS COMPANY, OF SYRACUSE, NEW YORK, A CORPORATION OF NEW YORK.

ELECTRICAL APPLIANCE FOR PANEL-BOARDS.

1,218,407.

Specification of Letters Patent.

Patented Mar. 6, 1917.

Application filed July 2, 1912, Serial No. 707,147. Renewed June 23, 1914. Serial No. 846,877.

To all whom it may concern:

Be it known that I, RALPH E. JONES, of Syracuse, in the county of Onondaga and State of New York, have invented a new and useful Electrical Appliance for Panel-Boards, of which the following is a specification.

This invention has for its object the production of an electrical appliance as a push button switch particularly applicable for use in connection with panel boards, and it consists in the combinations and constructions hereinafter set forth and claimed.

In describing this invention reference is had to the accompanying drawing in which like characters designate corresponding parts in all the views.

Figure 1 is a plan view of the base of this electrical appliance, and parts carried thereby, the same being shown as mounted upon a panel board.

Fig. 2 is a transverse sectional view of this electrical appliance and contiguous parts of the panel board.

Fig. 3 is a plan view of the base, the switch being removed.

Fig. 4 is a perspective view of one of the contact terminals.

1 is the base, which is here shown as rectangular and in the form of a box having its bottom adapted to be mounted on the panel board, the box being open at its top.

2 is the cap or cover for the box, the cap entirely inclosing the top and upright sides of the box and having its sides skirting the side faces of the box and adapted to rest upon the panel board, the cap and base having interlocking means for resisting removal of the cap and holding the cap with its lower edges engaged with the base of the panel board.

3 and 4 are pairs of terminals located in the box 1. 5 and 6 are switch arms for coacting with the pairs of terminals 3, 4; and 7 and 8 are push buttons for operating the switch arms, said push buttons extending upwardly beyond the top of the base 1 and through holes in the top of the cap 2.

As here shown each terminal 3 or 4 is angular in form and has one portion 9 thereof engaging the inner face of one of the side walls of the box 1 and another portion lying on the bottom of the box 1 and held in position by a screw 10 extending through the bottom from the rear side thereof and into

said terminal, the portion 9 extending laterally beyond the plane of the inner edge of the other portion of said terminal and carrying spring arms or switch contacts 11 which extend downwardly to the bottom of the box at a point spaced apart from said inner edges, and substantially midway between said edges and the opposing surfaces of ribs 14 and 15 hereinafter described. The portions 9 of the terminals of each pair are located on opposing side walls of the box 2.

As here shown the bottom of the box 1 includes raised ledges 12 on other opposite sides thereof on which the terminals 3, 4 are mounted and through which the screws 10 extend, opposing ends of each pair of terminals 3, 4 being separated by barriers 13 on said ledges 12.

The box is also formed with vertically extending ribs 14 projecting into the interior thereof from the sides on which the portions 9 of the terminals are mounted, and with a rib 15 connecting the lower ends of the ribs 14, the ribs 14, 15 being located midway between the ledges 12 and serving as barriers 80 between the terminals 3 and the terminals 4.

16 is a bridge or support forming part of the switch, the bridge extending across the upper end of the box 1 and resting at its outer ends on the upper ends of the ribs 14, 85 and being held in position by screws 17 extending vertically into said ribs 14.

The bridge 16 supports the switch mechanism including the knife arms 5 and 6, push buttons 7 and 8 and the interposed mechanism between the push buttons and the arms. The push buttons extend upwardly through holes in said bridge.

The base is held in position on the panel board by fastening members, as screws 18, 95 extending through the terminals 3, 4 and ledges 12, and threading into the offset ends 19 of bus bars 20, 21 of the panel board, the screws 18 serving to electrically connect the terminals to the bus bars 20, 21 and mechanically connect the electrical appliance to the panel board. The heads of said screws are located within the box so that they are accessible from the front side or open top thereof. Thus the electrical appliance can be readily attached to the panel board from the front side thereof.

The cap 2 is preferably held in position by means of a snap catch or catches carried by the box on the outer sides thereof, each 110

catch comprising a spring tongue 22 coacting with depressions 23 on the inner faces of sides of the cap 2 and having an angularly arranged lug 24 extending into a recess 25 formed in the box 1 and opening through the outer face thereof. The recesses 25 extend into the ribs 14 at the lower ends of the passages for the screws 17 so that the screws 17 coact with the lugs 24 and hold the snap 10 catches in position, the lower ends of the screws threading into nuts 26 located in said recesses below the lugs 24.

What I claim is:

1. An electrical appliance comprising a base in the form of a box, terminals in the box, a switch arm for coacting with the terminals, a cap for the box having its sides skirting the sides of the box, a push button extending through the cap, and spring 15 pressed interlocking means interposed between the sides of the cap skirting the box and the sides of said box, for holding the cap in position, substantially as and for the purpose set forth.
2. The combination with a support, of an electrical appliance comprising a base in the form of a box mounted on the support and having its top open, terminals in the box, a switch arm in the box for coacting with the terminals, means within the box for securing the same to the support, said means being removable through the open top of the box, a cap for the box having a top and sides, the sides of the cap skirting the sides of the box 30 and having their lower edges resting on the support, and a push button connected to the switch arm for actuating the same, the push button extending beyond the top of the box and through the top of the cap, substantially 35 as and for the purpose described.
3. The combination with a base and electrical conductors fixed thereon, of an electrical appliance comprising a base in the form of a box mounted on the electrical conductors and having its top open, terminals in the box, a switch arm in the box for coacting with the terminals, means within the box for securing the same to the electrical conductors, said means being removable 45 through the open top of the box, a cap for the box having a top and sides, the sides of the cap skirting the sides of the box and having their lower edges resting on the first-mentioned base, and a push button connected 50 to the switch arm for actuating the same, the push button extending beyond the top of the box and through the top of the cap, substantially 55 as and for the purpose specified.
4. The combination with a support, of an electrical appliance comprising a base in the form of a box mounted on the support and having its top open, terminals in the box, a switch arm in the box for coacting with the terminals, means within the box for securing 60 the same to the support, said means being

removable through the open top of the box, a cap for the box having a top and sides, the sides of the cap skirting the sides of the box and having their lower edges resting on the support, a push button connected to the switch arm for actuating the same, the push button extending beyond the top of the box and through the top of the cap, and means for detachably securing the cap to a side of the box, substantially as and for the purpose 75 set forth.

5. The combination with a base and conducting bars fixed thereon, of an electrical appliance comprising a base in the form of a box having its top open, a pair of terminals 80 within the box having portions lying on the bottom of the box, switch means coacting with the terminals, and fastening members extending through said portions of the terminals and through the bottom of the box 85 and engaging the conducting bars for mechanically connecting the box to the first-mentioned base and electrically connecting the terminals to the conducting bars, substantially as and for the purpose specified. 90

6. The combination with a base and conducting bars fixed thereon, of an electrical appliance comprising a base in the form of a box having its top open and its bottom including raised ledges along opposite sides 95 thereof, terminals arranged in pairs in the box and portions of each pair engaging opposite ends of one of the ledges, switch means coacting with the terminals, screws securing said portions of the terminals to the 100 bottom, and additional screws extending through said portions of the terminals, the ledges and the bottom of the box and engaging the conducting bars for mechanically connecting the box to the first-mentioned 105 base and electrically connecting the terminals to the conducting bars, substantially as and for the purpose set forth.

7. An electrical appliance comprising a base in the form of a box and having its top 110 open, a pair of terminals in the box, each terminal being angular in form and having a substantially horizontal portion mounted upon a surface provided on the bottom of the box, and having another portion extending 115 upwardly beyond the first-mentioned portion and laterally beyond the plane of a side edge thereof, a switch contact carried by the laterally extending part of the second-mentioned portion of the terminal and terminating at 120 one side of the plane of said side edge of the first-mentioned portion of said terminal, and a switch-arm in the box arranged to engage the contacts of the terminals, substantially as and for the purpose described. 125

8. An electrical appliance comprising a base in the form of a box and having its top open, a pair of terminals in the box, each terminal being angular in form and having a substantially horizontal portion fixed upon 130

- a surface provided on the bottom of the box near one side thereof, and having another portion extending upwardly beyond the first-mentioned portion and laterally beyond the first-mentioned portion and laterally beyond the plane of the inner edge thereof and engaged with a side of the box at an angle to said side of the bottom, a switch contact carried by the laterally extending part of the second-mentioned portion of the terminal and extending downwardly toward the bottom of the box at the inner side of the first-mentioned portion of the terminal, and a switch-arm in the box arranged to engage the contacts of the terminals, substantially as and for the purpose specified.
9. An electrical appliance comprising a base in the form of a box and having its top open, the bottom being formed at opposite sides with raised ledges, a pair of terminals in the box, each terminal being angular in form and having a substantially horizontal portion mounted on one of the ledges of the bottom of the box, and having another portion extending upwardly beyond the first-mentioned portion and laterally beyond the plane of the inner edge thereof and engaged with a side of the box at an angle to the ledges, switch contacts carried by the laterally extending parts of the second-mentioned portions of the terminals and extending downwardly into contact with the bottom between-said ledges, fastening screws for securing the first-mentioned portions of the terminals to the ledges, and a switch-arm in the box arranged to engage the contacts of the terminals, substantially as and for the purpose set forth.
10. An electrical appliance comprising a base in the form of a box having its top open, a pair of terminals in the box, each terminal being angular in form and having portions arranged to engage respectively one side and the bottom of the box, a switch contact carried by the portion engaging the side of the box, fastening screws extending through the portions of the terminals lying on the bottom of the box, screws extending through the latter portions and designed to attach the box to its support and to connect the terminals in an electric circuit, and a switch arm in the box and arranged to engage the contacts of the terminals, substantially as and for the purpose specified.
11. An electrical appliance comprising a base in the form of a box having its top open, the box being formed with inwardly extending vertical ribs on opposite sides thereof and with a rib on the bottom connecting the lower ends of the vertical ribs, pairs of terminals located in the box on opposite sides of the ribs including switch contacts, and a switch comprising a supporting bridge extending across the top of the box and resting at its ends upon the upper ends of the vertical ribs, the switch including a pair of arms located on opposite sides of the ribs in position to coact with the contacts of the pairs of terminals, substantially as and for the purpose set forth.
12. An electrical appliance comprising a base in the form of a box, the bottom of the box having raised ledges extending along opposite sides thereof, and the box being formed with vertical ribs on other sides thereof and with a rib on the bottom connecting the lower ends of the vertical ribs, pairs of terminals located in the box on opposite sides of the ribs, the terminals including portions mounted on the ledges and other portions engaging the sides of the box formed with the first-mentioned ribs, the last-mentioned portions of the terminals being provided with switch contacts having their engaging ends disposed between the planes of opposing surfaces of the ledges and the ribs, and switch means coacting with the terminals, substantially as and for the purpose described.
13. An electrical appliance comprising a base in the form of a box, the bottom of the box having raised ledges extending along opposite sides of the box, and the box being formed with vertical ribs on other opposite sides of the box and located between the ledges, pairs of terminals located in the box each being angular in form and having a portion engaging the side of the box formed with one of said ribs and provided with a switch contact and another portion lying on the contiguous ledge of the bottom and secured thereto, a switch comprising a bridge extending across the top of the box and resting on its ends on the upper ends of the ribs, the switch including arms located in the box on opposite sides of the ribs and coacting with the contacts of opposing terminals, screws passing through the bottom of the box and into the portions of the terminals lying on the ledges of the bottom, and screws extending through said portions of the terminals, the bottom of the box and designed to connect the terminals in an electric circuit and to secure the box in position, the heads of the latter screws being exposed in the box, substantially as and for the purpose described.
14. An electrical appliance comprising a base in the form of a box, terminals in the box, switch means coacting with the terminals, a cap for the box having its sides skirting the outer side faces of the box, yielding engaging means for holding the cap in position, said engaging means being carried on the outer side of the box and coacting with the opposing side surface of the cap, the box being formed with a recess opening through one of its outer side faces, and the yielding means having a lug extending into the recess, and a screw extending vertically on the side of the box and coact-

ing with said lug, substantially as and for the purpose set forth.

15. An electrical appliance comprising a base in the form of a box, a cap fitting over 5 the base and having the sides thereof skirt-
ing the outer side faces of the base, switch mechanism located in the box, a bridge sup-
porting the switch mechanism and resting upon upper edges of the box, a snap catch 10 located on the outer side of the box and co-
acting with the cap to hold the same in po-
sition, and means for fastening the bridge and the snap catch in position including a

member common to said bridge and snap catch, substantially as and for the purpose 15 set forth.

In testimony whereof, I have hereunto signed my name in the presence of two at-
testing witnesses, at Syracuse, in the county of Onondaga, in the State of New York, 20
this 3rd day of June, 1912.

RALPH E. JONES.
